COLLAPSIBLE CONTAINER

Clarence W. Vogt, Norwalk, Conn., assignor, by
mesne assignments, to Owens-Illinois Glass
Company, Toledo, Ohio, a corporation of Ohio

Original application April 15, 1936, Serial No.
74,424. Divided and this application March
15, 1938, Serial No. 195,954

10 Claims. (Cl. 229—14)

This application is a division of my prior application Serial No. 74,424 filed April 15, 1936.

This invention relates to containers which may be made and shipped in flat collapsed form, and which may be readily opened up and employed for the storage, shipment and dispensing of pourable or spoonable materials such as liquids and solids in powder or granular form.

One object of the present invention is to provide a new and improved container of the type referred to.

A further object is to provide a new and improved outer supporting structure for a flexible bag when said bag is charged.

The flexible bag may be so constructed that when collapsed it comprises a pair of flat walls of substantially equal areas, facing each other and forming a filling and pouring mouth at one end. A portion of this mouth is permanently sealed, and another, preferably the center portion, is unsealed prior to the filling operation and thereafter closed by a seal which may be readily broken without the use of tools, without mutilating the bag, and without in any way contaminating the inner surface of said bag.

The outer supporting structure which comprises the main novel feature of the present invention is a shell having six parallel fold lines, two of which are medial lines on opposite panels so that the shell may be collapsed by folding on the medial lines. The tubular liner is preferably so secured to the shell that when the latter is opened up or expanded to rectangular form, the liner is likewise opened up.

As a feature of the present invention, the bag is so constructed that when collapsed it will comprise a pair of opposed flat wall members separated by infolds to form the other two walls of the expanded bag and the shell likewise has a pair of opposed flat wall members separated by outfolds to form its other two walls when expanded.

Various other objects, features and advantages of the invention will be apparent from the following particular description and from an inspection of the accompanying drawing in which:

Fig. 1 is a perspective view of a flexible bag combined with the outer comparatively stiff arboard frame, and shows the bag after it has been filled and sealed and prior to confining the upper end of said bag within the contour of said outer frame structure.

Fig. 2 is a longitudinal section of the container shown in Fig. 1.

Fig. 3 is a perspective view showing the con-

tainer of Fig. 1, prepared for storage and transportation.

Fig. 4 is a top plan view of a shipping carton having a number of containers of Fig. 3 packed therein.

Fig. 5 is a side view, partly in section, showing the container in Fig. 1 in the process of dispensing into the crank case of an internal combustion engine.

Fig. 6 is a perspective view of the container of Fig. 3 after the major portion of the contents thereof has been discharged, and showing in section the partly collapsed bag, and

Fig. 7 is a perspective view of the upper end of the inner bag, and showing another manner in which the mouth of the bag may be sealed.

It must be understood that the thickness of the various layers of the flexible bag and shell are shown in the drawing somewhat exaggerated, and that in practice all of the layers of the bag are very thin. The flexible bag is preferably made from a continuous thin strip of flexible material, progressively assembled to form an endwise advanced tube, progressively collapsed, sealed transversely along the successive lengths thereof, and then transversely cut intermediate of the ends of the sealed portion to form a complete hermetically sealed collapsed bag.

The bag may be made of laminated or coated sheet material, the inner layers or coating of which are of such material that when said inner layers are superposed and pressed together under heat, they will weld, vulcanize or hermetically unite. As an example of such material, I

may and preferably do employ a type of thin, flexible, transparent, slightly elastic, impervious material sold under the name of "Pliofilm" and made from chlorinated rubber compound. This material has the thermoplastic characteristic of being readily vulcanized or sealed at a temperature of approximately 115° C., so that the overlapping sections thereof may be vulcanized or sealed together by the application of heat and pressure, even though the surfaces have been previously wetted by contact with liquids or moisture-carrying plastic material.

Another material which may be satisfactorily used in some constructions and for some material is a moisture-proof cellulosic material of the type sold under the trade name "Heat Sealing Cellophane". A thin sheet material having a waterproof coating or layer such as that sold under the trade name "Koroseal" may also be used. Also, other materials may be used, which may be fabricated into a casing by the use of adhesive

or solvents to sealably secure adjacent surfaces of said material together.

As the details of construction of the inner liner or bag per se form no portion of my present invention, it is here merely noted that the bag may have a laminated wall with an inner ply of impervious material and an outer ply of paper or the like secured together in any suitable manner. The bag may be made from an endless tube with one or more longitudinal seams and collapsed to form two opposed panels 25 and 26 and connecting infolded wall sections 27. The tube may be transversely sealed along narrow strips and cut into sections to form the bags or liners, closed at the bottom and having a top opening between the opposed panels so that the upper edges may be sealed together as at 16 after filling. Preferably the opening at the top extends only to the infolds and it is only along this section that the bag is opened as shown at 15 in Fig. 6 for discharging the contents. As the opening does not extend across the entire width of the top, the opening may be closed by a clip 84 as shown in Fig. 7 instead of or in addition to being sealed. The walls of the bag may be cut below the clip to open the bag or the clip may be attached only sufficiently friction-tight to permit it to be pulled off.

The present invention includes a new and improved outer relatively stiff frame structure 18 for protecting the flexible bag during handling, storage and transportation. In Figs. 1 to 6, the outer frame structure is shown applied to the bag of the form above referred to but it must be understood, however, that as far as the present invention is concerned, the bag may be of any other similar type. In the specific form shown, the outer frame structure is in the form of a collapsible cardboard tube open at both ends and having a rectangular cross-section when set up corresponding to the cross section of the distended inner bag. This frame tube 18 is collapsed and expanded with the inner bag, and for that purpose has a pair of opposed panels 11 cemented, or otherwise secured to the corresponding front and rear walls of the inner bag and interconnected by the panels 12 on the infolded sides of said bag. These panels 12 are provided respectively with medial longitudinal score or crease lines 13 to permit the easy outward folding of said panels. When collapsed, the two panels 11 will come together and the two panels 12 will be folded outwardly along their crease line 13 and portions 27 of the bag will be infolded in the condition shown in Fig. 6. It will be noted that the outer element has six score lines and the inner element has six fold lines to permit this collapsing.

The combined frame tube and inner bag is shipped or delivered to the filler in collapsed flattened condition. The operator sets up the collapsed tube 18 and charges the inner bag through its upper end. The collapsed frame tube and bag are so correlated as to eliminate the necessity of setting up said frame tube preliminary to the filling operation since the expansion of the bag during this filling operation causes the corresponding expansion of said frame tube.

The bag when collapsed has its lower end extending below the lower end of the frame tube 18. As the bag is filled, this lower projecting end of the bag gradually moves up until the bottom 75 of the distended bag rises to a position approxi-

mately in the plane of the lower end of said cardboard frame as shown in Figs. 1, 2 and 3.

After the bag has been filled, the open mouth thereof is sealed along a narrow strip in a manner as above described and the flap of said bag along the upper seam 15 may have an inclined position shown in Figs. 1 and 2 and may be further folded down as shown in Fig. 3.

In order to hold the collapsible cardboard frame 18 in set-up position after the bag has been filled, there is provided a cloth or paper tape 16 adhesively secured at its ends to the collapsible panels 12 and tautly stretched across the lower end of the frame tube. The upper end of the cardboard frame 18 may be similarly provided with a tape 17 stretched between the collapsible panels 12 to form the shippable package shown in Fig. 3. These tapes 16 and 17, besides holding the frame tube 18 in set-up condition, also serve to hold the ends of the bag within the confines of the cardboard frame 18.

In the shipment and storage of the containers shown in Fig. 3, it is customary to have a number of these containers closely packed together in some sort of carton 18 as shown in Fig. 4, so that it is difficult or impossible to grasp the sides of these containers and pull them out of the pack. In order to permit a container to be easily extracted from such a close pack, the upper end of one of the panels of the cardboard frame 18, as for instance the panel 11, is provided with an arcuate notch 19 (see Fig. 3) and these containers are so packed in the shipping carton 18 that the notched panel of one container is adjacent to an unnotched panel of an adjacent container. By this means the portion of the panel of one container opposite to the notch of a panel of an adjacent container may be grasped by the fingers to pull out said former container from the close pack.

A container as shown in Fig. 3 may be used for a variety of purposes. Such a pack for instance, has a great deal of adaptability for the purpose of holding crank case oils since it lends itself to easy dispensation. In Fig. 5 is shown a manner in which a container such as that shown in Fig. 3, containing lubricating oil, may be easily dispensed from for the purpose of filling the crank case of an automobile engine. For that purpose, there is shown a conduit 80 leading into the crank case of the engine. Extending into said conduit is a funnel 81 having one or more clips 82 in the inner side of the flared portion thereof for supporting a container therein. When it is desired to fill the crank case of the motor, the funnel 81 is placed in the conduit 80. The upper and bottom tapes 16 and 17 of a container are then torn or removed, and the seal between the pouring lips of the mouth broken by the simple manipulation of separating the parallel lips. However, the breakable seal between the mouth lips may be such that when the container is inverted into pouring position, the impact of the oil against the seal may be sufficient to break the seal. The container with either type of mouth seal is placed in the funnel 81 so that the clips 82 grasp the end portion of one of the frame panels 11 projecting beyond the portion where said panel is adhesively secured to the corresponding wall of the bag as shown in Fig. 5. As the contents of the bag is discharged, the bag will automatically collapse into flattened condition, and since the front and rear walls of the inner bag are connected to the panels 11 of the

frame tube, this collapse of the inner bag causes the corresponding collapse of the frame tube. When fully discharged, the container will be in the collapsed condition although shown in only partly collapsed condition in Fig. 6, and will occupy the minimum amount of refuse space.

Having thus described my invention, what I claim as new and desire to secure by Letters Patent is:

10. 1. A container including a flexible bag having a pair of lips adapted to form an opening communicating with the interior of said bag, said lips having a readily breakable seal, whereby said lips may be used as a pouring spout, and an outer supporting frame structure for said bag, permanently secured thereto, said frame structure being open at its upper end.

20. 2. A package including a bag of flexible material containing dispensable materials, an outer readily collapsible supporting frame structure for said bag, permanently secured thereto, and easily breakable means for holding said bag in expanded condition for shipment and storage.

25. 3. A package including a flexible bag containing material, and an outer tubular supporting open-ended frame structure for said bag, said frame structure having a pair of opposed walls provided with medial crease lines whereby said frame structure may be collapsed into substantially flat condition as the contents of the bag are discharged, and a readily breakable tape tautly stretched across one end of said frame structure and having the ends thereof secured to said walls for holding said frame structure in expanded condition.

35. 4. A package including a flexible bag containing pourable material, and an outer tubular supporting open-ended frame structure, said frame structure having a pair of opposed walls provided with medial crease lines whereby said frame structure may be collapsed into substantially flat condition as the contents are discharged, and a pair of readily breakable tapes stretched respectively across the open ends of said frame structure and having the ends thereof secured to said walls for holding said frame structure in expanded condition.

45. 5. A package including a flexible bag containing lubricating oil, an outer tubular supporting frame structure permanently secured to said bag, open at both ends, and having a pair of opposed walls provided with medial crease lines whereby said frame structure may be collapsed into substantially flat condition as the oil is dis-

charged, and easily breakable means for supporting said frame structure in expanded position.

6. A container comprising a flat folded supporting shell and an inner liner each having six parallel fold lines, two of which are medial lines on opposite two panels and being folded on the medial lines, the folds on the medial lines of the shell being outwardly, and the folds on the medial lines of the liner being inwardly, and the liner being secured to the shell whereby when the shell 10 is erected it results in a rectangular shaped container and opens up the liner.

7. A container comprising a flat folded supporting shell and an inner liner each having six parallel fold lines, two of which are medial lines 15 on opposite two panels and being folded on the medial lines, the liner being secured to the shell whereby when the shell is erected it results in a rectangular shaped container and opens up the liner, and a transverse member secured to the 20 said panels of the shell which have the medial fold lines, and normally preventing outward folding on said lines.

8. A package including a flexible bag and an outer tubular supporting open-ended frame 25 structure for said bag, said frame structure having a pair of opposed walls provided with medial crease lines whereby said frame structure may be collapsed into substantially flat condition as the contents of the bag are discharged, and a member 30 extending across one end of said frame structure and having the ends thereof secured to said walls for holding said frame structure in expanded condition.

9. In combination a container having flexible 35 walls and an outer tubular supporting frame structure encircling said container and having a pair of opposed walls provided with medial crease lines, whereby said frame structure may be collapsed into substantially flat condition, and a 40 member secured to said walls and normally preventing said collapsing.

10. In combination a container having flexible 45 walls and an outer tubular supporting frame structure encircling said container and having a pair of opposed walls provided with medial crease lines, whereby said frame structure may be collapsed into substantially flat condition, and a pair of flexible members extending across opposite ends of the frame structure and connected to said walls and normally preventing collapsing 50 of the frame structure and protecting the ends of said container.

CLARENCE W. VOGT.
